UNITED STATES PATENT OFFICE.

JAMES WILLIAM BOOTH AND THOMAS CRAVEN CORLASS, OF KEIGHLEY, ENGLAND.

LET-OFF MECHANISM FOR LOOMS.

Application filed January 23, 1922. Serial No. 531,078.

To all whom it may concern:

Be it known that we, JAMES WILLIAM BOOTH and THOMAS CRAVEN CORLASS, subjects of the King of Great Britain, and residents, respectively, of Mount Royd, Highfield Lane, Keighley, in the county of York, England, and 5, Sunny Mount, Keighley, aforesaid, have invented a certain new and useful Improvement in Let-Off Mechanisms 10 for Looms, of which the following description, together with the accompanying sheets of drawings, is a specification.

It relates to let-off mechanism for looms of the type or class known as friction let-off mechanism and of the particular kind wherein the diameter of the coils of warp around the warp beam controls or regulates the friction which retards the rotary motions of said warp beam, and our said invention consists in a novel formation and construction of lever devices and mechanism for altering certain of the fulcrums of same so as to vary the power or force exercised by said levers (and therefore the friction which acts) upon the warp beam to retard its motions.

In the accompanying sheets of drawings which are illustrative of our invention—

Fig. 1 is a sectional end elevation of a portion of the framework of a loom and the warp beam mounted thereon with our improved mechanism applied thereto.

Fig. 2 is a rear elevation of the apparatus shown by Fig. 1 as seen in the direction looking from right to left of said figure.

Fig. 3 is a plan of parts shown by Fig. 1.

Fig. 4 is a sectional elevation of certain of our improved parts.

Fig. 5 is a plan of the parts shown by Fig. 4.

Fig. 6 is a sectional end elevation showing the formation of a bracket for supporting the fulcrum of the weighted lever which acts upon the brake of the warp beam.

The drawings show our apparatus upon one end of a warp beam, however we may use same at both ends thereof when desired.

Our invention is shown as applied to an ordinary loom wherein the warp beam 3 is mounted in the usual manner upon bearings fixed to the end frame 7 of the loom so that the warp 3^a may be withdrawn therefrom under such conditions that as same is being carried out the well known detector lever 8 (which rests against the coils of warp 3^a) is made to control the novel devices

hereinafter described, as it moves from the position shown in full lines Fig. 1 to the position shown in broken lines of the same figure, by which the object of our invention 60 is attained.

In connection with the said warp beam and other parts we make use of a chain, rope or other friction imparting device 2 which according to the drawing encircles 65 the end of the warp beam 3 or which may encircle pulleys or drums mounted thereon as is well understood. This friction device in the form of the chain 2, is coupled by a hook 18^a to the end of a weighted lever 4, the weight 4^b of which acts thereon so that the power of said weight 4^b over the hook 18^a and consequently over the gripping chain 2, is exerted through said lever 4, which rests with its fulcrum upon the bowl 70 or runner 5 at the point 4^a shown by Fig. 4.

The runner or bowl 5 is supported by the bracket 6 which is fixed to the end frame 7 of the loom so that as said bowl 5 is permitted to move over the bracket 6 from the position shown in full lines Fig. 2 to the position shown in broken lines of the same figure, the relative lengths of the arms of the lever 4 are altered so that the power of the weight 4^b over the brake chain 2 is 85

This diminishing of the power of the weight 4^b over the brake 2 is gradually brought into effect as the diminished diameter of the coils of warp 3^a upon the beam 3 decrease in number and therefore in diameter and this is effected by coupling the detector lever 8 to the bowl 5 under such conditions as to enable the weight 14^a 90 to carry said bowl 5 over the supporting bracket 6 in the manner above-stated.

The detector lever 8 is pivoted upon a shaft 9 which is supported in suitable bearings by the framework of the loom so that at the other end of the shaft 9 another lever 10 may be fixed. This lever 10 is connected by a flexible connection 11 to a cam piece 12 (the functions of which are hereinafter described) which is pivoted upon bearings 100 fixed upon the end frame of the loom as shown by Figs. 1 and 2, and the said flexible connection extends over this cam piece 12 so that by a cross piece 13, two other flexible connections 14 and 14^a may be joined to it and be made to extend over guiding pulleys 15, 15^a so that these latter may be connected to links 16, 16^a which take loosely 105 110

over the pin 5^a upon which the bowl 5 is pivoted.

The links 16, 16^a are further connected to a cross piece *c* by appropriate connections so that the extension 14^a of the flexible connections may pass over the guide pulley 15^b to support the weight 14^c. By these several parts being arranged as described, as the coils of warp 3^a upon the beam 3 diminish 10 in number to permit the lever 8 to follow said diminishing diameter said movements of the lever 8 are carried out by the weight 14^c dragging the bowl 5 along the bracket 6.

To enable the bowl 5 to move freely under 15 the actions of the weight 14^c as above described, we mount upon the pin 5^a (which has the bowl 5 mounted upon it) two bowls 17 and 17^a one at one side and the other on the other side thereof, and these bowls 17, 20 17^a are of less diameter than the bowl 5 (the slot *d* in the bracket 6 being arranged to receive the larger diameter bowl 5) so that they alone are in contact with the upper surface of the bracket 6 while the upper surface 25 of the periphery of the bowl 5 supports the lever 4 by the lower edge of said lever 4 resting thereon, thus as the weight 14^c drags the pin 5^a along its horizontal path, the bowls 17, 17^a roll over the upper 30 surface *b* of the bracket 6 while the bowl 5 rolls beneath (and in an opposite direction) the lower edge of the lever 4 by which arrangement the greatest freedom for the actions of the parts described is secured. To 35 secure further freedom for the actions of the bowls 5 and 17, 17^a the upper surface *b* of the bracket 6 is slightly inclined to the horizontal plane the inclination being shown by the difference between the path indicated in broken lines A B and the path 40 over the upper surface *b* of the bracket 6. Further than this the inclination of the lower edge of the lever 4 is in the opposite direction to that of the upper surface of the bracket *b* somewhat as is shown by the 45 broken lines C D as compared with said under surface of the lever 4 thus the moving of the bowls described is greatly facilitated.

To further facilitate the rotations of the bowls 17, 17^a and 5, antifriction bearings 50 may be used in conjunction with these said bowls or runners so that they may more freely revolve about the pin 5^a.

The lever 4 has its extremity of a bifurcated form so that the extension of the hook 18^b may take through same and through a pivotal part 18^c to have the adjusting nut 18 mounted upon it at its upper end, thus the position of the lever 4 may be adjusted 60 relatively to the parts in connection with which it has to operate. The end of the bracket 6 is bifurcated to receive the T-shaped extension 41 of the lever 4 as shown by Figs. 2 and 3, by which means said lever 65 is retained in position,

In order to keep the proper ration of variation between the diameter of the coils of warp 3^a upon the beam 3 and the leverage of the arms of the lever 4 (as brought about by the moving of the fulcrum bowl 5 beneath 70 the lever 4) we mount the intervening cam piece 12 in the position shown, and we form it of such a character as to enable it to keep the desired ratio intact throughout. It has been found in practice that unless the cam 75 12 is provided the diminishing diameter of the coils of the warp on the beam will not permit the movement of the weight over the weighing lever in the exact proportion desired, because the decreasing diameter cannot be apportioned to the decreasing leverage in any exact ratio. Therefore, the cam 80 12 is provided, and this also serves to keep taut the flexible connection between the lever 10 and the cross piece 13.

In order to enable the weaver to readily release the beam 3 from the grip of the brake devices, we mount a cam like hand lever 19^a upon the bracket 6 in order that by the actuation of this lever 19^a the weaver 90 may cause the cam part 19 to pass beneath the bowl or runner 20 mounted upon the lever 4 so as to raise said lever and relieve the chain 2 of the force exerted thereby.

In the accompanying description and as 95 shown by the sheets of drawings we have illustrated the brake or friction device as consisting of a chain which encircles the hub on the end of the warp beam 3, but it is obvious that we make use of rods or shoe or 100 clamping devices of any of the varied well known forms instead of using said chain in which case the connecting device will be made to suit the altered form of friction device.

Such being the nature and object of our said invention, what we claim is:

1. In let-off mechanism for looms, a warp beam, a brake device engaging with said warp beam, a weighted lever acting upon said brake device, a movable fulcrum for said weighted lever, means for connecting said movable fulcrum to a detector contacting with the coils of warp on the warp beam, and means for keeping said detector against said warp beam.

2. In let-off mechanism for looms, a warp beam, brake mechanism engaging with said warp beam, a weighted lever for operating said brake mechanism, connections between said lever and said brake mechanism, a bowl or runner forming the fulcrum for said brake lever, a bracket for supporting said bowl or runner, connections between said bowl or runner and a detector which contacts with the coils of warp on the warp beam, whereby the fulcrum of the brake lever is positively moved along the supporting bracket as the diameter of the warp coil is reduced, and a weight for operating said runner to keep the 130

detector in contact with the coils of warp on the warp beam.

3. In let-off mechanism for looms, a warp beam, a flexible brake device encircling said warp beam, connections from said flexible brake device to a weighted lever, a movable support upon which the brake lever is pivoted, means for moving said support in accordance with the diminishing diameter of the coils of warp on the warp beam, and a detector device in conjunction with said means for operating the movable support.

4. In let-off mechanism for looms, a warp beam, a brake device engaging with said warp beam, a weighted lever for operating said brake device, a movable fulcrum for said weighted lever, means for effecting movement of said movable fulcrum in accordance with the diminishing of the diameter of the coils of warp upon the warp beam, and a cam piece cooperating with said fulcrum moving means to retain the ratios of the leverage and the diameter of the warp beam constant.

25 5. In let-off mechanism for looms, a warp beam, a brake device in connection with said

warp beam, a weighted lever operating said brake device, a movable fulcrum for supporting said weighted lever, bearings for supporting said movable fulcrum, sets of bowls or runners for intervening between the bearings of the lever so as to act as said movable fulcrum, and means for operating said bowls.

6. In let-off mechanism for looms, a warp beam, brake mechanism for engaging with said warp beam, a weighted lever for operating in connection with said brake mechanism a movable support upon which the weighted lever is pivoted, said support being arranged so that it may be adjusted to decrease the force of the weighted brake mechanism as the diameter of the coils of warp upon said warp beam diminish, and means whereby said diminishing diameter of warp threads is detected and used for controlling the position of the support for the lever, in combination with hand actuated devices whereby the weaver may relieve the brake from the actions of the weight.

JAMES WILLIAM BOOTH.
THOMAS CRAVEN CORLASS.
